United States Patent Office

Des. 205,104
Patented June 21, 1966

205,104

PROJECTION VIEWER

Richard J. Olson, Pittsford, N.Y., assignor to Eastman
Kodak Company, Rochester, N.Y., a corporation of
New Jersey

Filed Apr. 1, 1965, Ser. No. 84,567

Term of patent 14 years

(Cl. D61—1)

FIG. 4

FIG. 5

FIG. 1 is a front perspective view of a projection viewer showing my new design, in open or operative condition;

FIG. 2 is a rear perspective view thereof;

FIG. 3 is a bottom plan view thereof;

FIG. 4 is an end view thereof in its closed condition; and

FIG. 5 is a side view thereof in its closed condition.

I claim:

The ornamental design for a projection viewer, as shown.
